UNITED STATES PATENT OFFICE.

EDWIN RUUD, OF PITTSBURG, PENNSYLVANIA.

PILOT-LIGHT BURNER FOR WATER-HEATERS.

968,605.

Specification of Letters Patent. Patented Aug. 30, 1910.

Application filed February 1, 1908. Serial No. 413,825.

To all whom it may concern:

Be it known that I, EDWIN RUUD, of Pittsburgh, in the county of Allegheny and State of Pennsylvania, have invented a certain 5 new and useful Improvement in Pilot-Light Burners for Water-Heaters, of which improvement the following is a specification.

My invention relates to burners, of the class known as pilot light burners, which are 10 used in water heaters for maintaining the combustion of a comparatively small supply of gas during the periods of inaction of the heater in order to ignite gas automatically supplied to the main burners when water is 15 to be heated.

The object of my invention is to provide a burner of this class which shall be simple, inexpensive, and durable, and which shall further be exempt from the serious objection 20 of becoming clogged in service, which is manifested to a substantial degree in burners of the ordinary construction.

The improvement claimed is hereinafter fully set forth.

25 The pilot burner, while a simple and comparatively unimportant member of an automatic water heater, is one which it has been found difficult to construct and maintain in reliable working condition, and 30 which has been the subject of considerable study and experiment on the part of water heater manufacturers.

The form of pilot burner which has, prior 35 to my invention, been considered to be the most satisfactory one, is made in three parts, consisting of a lower casting connected to the gas supply pipe, a middle portion of porcelain, having a set of gas discharge orifices, and a metal top held down by a screw.

40 This construction is, however, objectionable both as to cost of construction and lack of durability. The metal top is soon destroyed by the action of the carbon in the gas at high temperature, the screw burns away, 45 and the porcelain cracks and becomes useless, the expense and annoyance of frequent renewals being thereby necessitated. These objections are wholly obviated by my invention and the further advantage of simpler 50 and cheaper construction is also attained.

In the accompanying drawings: Figure 1 is a vertical central section through a pilot burner embodying my invention; Fig. 2, a

horizontal section through the same, on the line X—X of Fig. 1; and Fig. 3, a vertical 55 central section illustrating a structural modification.

In the practice of my invention, I provide a burner having a cylindrical body, 1, and a head, 2, of larger diameter which are 60 formed integrally from a block or section of suitable refractory material, such as soap-stone, fire-clay, porcelain, or graphite composition. A central gas supply passage, 3, is formed in the body, 1, and a plurality of 65 burner orifices, 3^a, extend from said passage, near its top, to the periphery of the body. The head, 2, is preferably of conical form, and is of sufficiently larger diameter than the body to shed any water that may drop 70 down upon the burner and prevent it from entering the burner orifices. A screw thread, 1^a, is cut upon the body, 1, at and adjoining its lower end, to provide for its connection to a short pipe section or nipple, 4, 75 leading from a gas supply pipe, said screw thread being shown in Fig. 1 as external, and engaging an internal thread at one end of a socket or fitting, 5, the joint between the body and socket being made tight by 80 an annular washer or packing ring, 6. A central bore or opening extends through the socket, 5, the end of which, farther from the burner body, is connected to the nipple, 4, by a screw thread. 85

The structural modification shown in Fig. 3, accords in all essential particulars with that above described, differing therefrom in dispensing with the connecting socket or fitting, 5, the screw thread, 1^a of the burner 90 body, 1, being, in this case, internal, and cut at the lower end of the gas supply passage 3, and the nipple, 4, being screwed thereto. The packing ring 6, is interposed between the bottom of the body and a collar, 4^a, on 95 the nipple, 4.

In operation, the gas from the supply pipe and nipple, 4, passes through the central passage, 3, and out through the burner orifices, 3^a, and is ignited as it passes into the 100 atmosphere at the outer ends thereof. The top of the burner, being of the same refractory material as the body, is not broken away or destroyed by the heat of the gas in operation, and the burner orifices are not 105 subject to being clogged by carbon or other

foreign matter which would adhere to a metal top.

The burner can be readily applied and detached, and the body may be made of ample strength to avoid liability to breakage.

I claim as my invention and desire to secure by Letters Patent:

1. The combination of an integral burner body and a conical shaped top of refractory material, the body being provided with a central gas passage and downwardly inclined communicating burner orifices, said top overhanging the burner orifices, a gas supply pipe having a screw threaded connection with the body, and a packing ring

closing the joint between the body and gas supply pipe connection.

2. The combination of an integral burner body and a conical shaped top of refractory material, the body being provided with a central gas passage and downwardly inclined communicating gas orifices, said top overhanging the burner orifices, and an internal screw thread, and a socket or fitting having a central gas passage and engaging the screw thread of the body.

EDWIN RUUD.
